UNITED STATES PATENT OFFICE.

GIACOMO BREDÉE, OF NEW YORK, N. Y.

BIRD-CAGE.

SPECIFICATION forming part of Letters Patent No. 326,841, dated September 22, 1885.

Application filed April 16, 1885. (No model.)

To all whom it may concern:

Be it known that I, GIACOMO BREDÉE, a citizen of the United States, residing at New York, in the county and State of New York, 5 have invented new and useful Improvements in Bird-Cages, of which the following is a specification.

This invention consists, first, in the combination, with a bird-cage, of supporting-legs 10 therefor provided with sockets constructed to receive objects, such as flower-pots; and, second, in a bird-cage having a sliding drawer, feed-cups secured in the drawer, and supporting-legs provided with sockets to receive objects, such as flower-pots.

Figure 1 is an elevation, part in section, of my improved bird-cage. Fig. 2 is a horizontal section of the same in the plane xx , Fig. 1. Fig. 3 is a vertical section through the drawer.

20 Similar letters indicate corresponding parts.

In the drawings, the letter A designates the top portion of the cage, which may be made of any shape or material, and B is the bottom, which, in the example shown in the drawings, 25 is permanently secured to the top portion of the cage; but, if desired, it may be made detachable.

C is the drawer, which is slid in the bottom of the cage, a suitable aperture, a , being left 30 in one of the sides of the bottom for that purpose, and in this drawer are secured, either permanently or detachably, to one of its sides, the feed-cups.

In order that the cage may be placed on a 35 table or the like, instead of being hung up, I provide the same with legs E, extending outwardly from the base of the cage, and each of which is provided with a hollow portion or socket, b , adapted to receive a flower-pot,

Fig. 1, or the like, whereby the artistic effect 40 of the cage is heightened. The legs may be riveted to the bottom or brazed to the same in any manner familiar to those skilled in the art.

It will appear evident that if the cross-section of the cage is made circular the aperture a must extend nearly half-way around the girth of the bottom, in order that the drawer B can be slid in and out.

In practice the drawer is made to extend 50 almost completely across the bottom in both directions, in order that all seed, water, or dirt may accumulate thereon and not fall on the bottom of the cage.

The object of my invention is to provide for 55 a cage which can be easily kept clean, and can be cleaned without disturbing the bird, while at the same time the feeding of the bird is facilitated by having the feed cups in the tray.

What I claim as new, and desire to secure by 60 Letters Patent, is—

1. A bird cage having supporting-legs projecting outwardly from its base and provided in their outer ends with sockets b , for receiving flower-pots, substantially as described. 65

2. As a new article of manufacture, a bird-cage having a sliding drawer, feed-cups secured in said drawer, and legs provided with sockets to receive flower-pots, substantially as shown and described.

In testimony whereof I have hereunto set my hand and seal in the presence of two subscribing witnesses.

GIACOMO BREDÉE. [L. S.]
